UNITED STATES PATENT OFFICE.

EDWARD H. RAPER, OF MAPLETON, IOWA, AND CHARLES E. RAPER, OF SHERIDAN, WYOMING.

VENTILATING CLOSET.

Application filed August 28, 1924. Serial No. 734,695.

This invention relates to improvements in the construction and operation of ventilators or deodorizers for water closets and other similar devices.

5 A primary object of the invention is to provide a ventilating device for removing the noxious gases from a closet bowl by means operatively connected with the closet seat and the supply pipe, so that upon the 10 seat being depressed, it will open a supply valve, thus causing a flow of fluid through a tube mounted within the ventilating chamber. The flow of fluid through the tube creating a suction in the chamber which draws 15 in the foul air from the bowl and conducts it to a suitable waste outlet. The device is so arranged and constructed that the spray and suction through the ventilating chamber will be automatically cut off or closed as soon 20 as the downward pressure on the seat is released.

A further object of the invention is to provide an injecting tube with means extending from its inner periphery into the path of the 25 stream for impeding the passage thereof and permitting the foul air to mix with the fluid as it passes through the tube to the waste outlet.

Another object of the invention consists in 30 the provision of means for preventing the water in the injecting tube from flowing back through the supply pipe in the event of the bowl running over when the main supply is shut off.

35 Referring to the drawings:

Figure 1 is a side elevational view of a 40 toilet bowl with our invention attached thereto.

Figure 2 is a plan view of Figure 1. 45 Figure 3 is an enlarged detailed view of Figure 1 with parts in section, for the purpose of clearness of illustration.

Figure 4 is a detail perspective view showing the means for actuating the supply valve.

45 Figure 5 is a sectional detailed view showing the connection of the interior of the bowl with the ventilating chamber.

Referring to the drawings, in which like 50 numerals indicate like parts in the several views, 10 denotes a water closet bowl of the ordinary construction and design, which is

provided with the usual flushing rim 11, having circumferentially spaced openings 12 for receiving the fluid which is conducted from the flushing tank 13 through the pipe 14.

A ventilating chamber 15, preferably positioned to one side of the bowl, communicates with the rim 11 through a passage 16, and has its lower end delivering to a waste outlet 16' in the trap portion and below the water line of the bowl, as indicated in dot and dash lines in Figure 5. Traversing the chamber 15 and removably supported therein is an injecting tube 17 provided with downwardly inclined perforations 18, preferably positioned adjacent its upper end, while a series of inclined blades extend from the inner wall of the lower portion of the tube so as to break up the stream and aerate the water as it passes through the tube.

It will be observed that the outlet 16 of the chamber 15 is so arranged relative to the bowl 10 as to permit the noxious gases to pass through the water standing in the bowl and be delivered to the waste outlet, during the ventilating operation. As the water in the bowl acts as a seal when the ventilator is working, there is no liability of the noxious gases or escaping sewer gases passing upward through the chamber 15 and contaminating the main supply. If, for any reason, the flushing device should become inoperative, the water seal will preclude the possibility of the noxious gases in the bowl escaping upwardly through the ventilating chamber 15.

A pipe 20, which directly communicates with the main supply 21, is preferably connected to the tube 17 by means of an exteriorly threaded nozzle 22, which has a downwardly tapered orifice 23 for delivering the fluid from the supply pipe 20 to the interior of the tube 17. An annular flange 24 is preferably positioned between the ends of the nozzle 22 so as to be engaged by the flange 25 on the coupling nut 26 that is threaded to the exterior of the extension sleeve 27. The sleeve 27 surrounds the upper portion of the tube, and is secured, at its lower end by the nut 28 to the chamber 15.

The tube 17 is preferably provided with an

annular tapered flange 29, which engages a correspondingly formed seat in a shoulder 30 projecting from the interior of the chamber 15 so that upon the tightening up of the 5 nut 26 on the sleeve 27, the lower portion of the tube will be maintained in proper position due to the wedging engagement of the flange 29 with the shoulder 30. It will be seen that by reason of this construction the 10 device may be readily dismantled and access had to the interior of the chamber and the ejector trap for inspecting or renewing the parts.

The seat 31 is preferably connected pivotally to a rearward extension 32 of the closet by means of the bolts 33, which extend through suitably spaced openings in the extension 32 and are secured to the under side thereof by the nuts 34, as shown in Figure 15 3. The upper ends of the bolts 33 are curved outwardly and connected together by a transverse fulcrum rod 35. The seat 31 carries a pair of rearwardly extending brackets 36, each of which has an upwardly extending arm 37, having a bearing eye which receives the rod 35 as shown in Figure 4. A valve operating lever 38 is provided at one end with an upwardly extending arm 39 (Fig. 4) pivoted on the rod 35. The 20 lever 38, when the seat 31 is raised, rests against a lug 40 which extends laterally from one of the bolts 33 so as to limit the downward movement of the lever. The opposite end of the lever 38 is secured to a 25 link 41 which is threaded to the lower portion of an arm 42 having a forked end 42' and is maintained in vertical adjustment relative to the arm by the nut 43.

An arm 44 connects the link 43 to the 30 supply control valve 45. The valve 45 may be of any conventional oscillating type, and is arranged to regulate the admission of the supply from the pipe 21 into the interior of the tube 18. A coil spring 46 is connected 35 at one end to an arm 47 secured to the underside of the bowl extension 32 by one of the bolts 33 while the opposite end of the spring is attached to the lever 38 so as normally to depress the lever and maintain the 40 valve 45 closed and the seat raised.

One of the seat brackets 36 is provided 45 with a tapered lug 48 which is in alignment with and frictionally engages a corresponding lug 49 formed integral with the lever 38, as shown in Figure 4, so that upon the seat being depressed when used by an occupant, it will cause the bracket 36 to move rearwardly, thus raising the operating lever 38, which opens the valve and allows fluid 50 to flow through the tube 17. Moreover, when the seat is not in use, depression of lever 38 by spring 46 will cause the lug 49 to push the lug 48 forwardly which will 55 raise the seat 31 and at the same time will close the valve 46.

The operation of the device is as follows:

The seat is normally in the raised position and the supply valve closed, as shown in Figure 3, due to the spring 46, forcing the lever 38 and its associated parts downwardly. Upon the seat 31 being depressed to the dotted line position shown in Figure 1, the bracket 36 (Figure 4) will swing about its fulcrum rod 35 causing the lever 38, the adjustable pin 42 and the adjacent end of the link 44 secured to the bifurcated arm 42, to be raised against the action of the spring 46 which will effect rotation of the valve stem connected to the opposite end of the link 45, thereby opening the valve 46.

As the water passes through the tube 17, it creates a suction in the chamber, which draws in the foul air from the interior of the bowl through the passage 16 and the inclined perforations 18. The passage of the 55 liquid through the tube will be impeded by the blades 19 which serve to effectively break up the stream and thoroughly mix the water with the foul air drawn into the interior of the tube.

When use of the seat is discontinued, the tension of the spring 46 will force the operating lever 38 and its associated parts downwardly, thereby closing the valve and at the same time the bracket 36 will be moved forwardly, thus raising the seat 31 to the position as shown in Figure 1.

In order to prevent the water from being drawn upwardly in the tube 17 and pipe 20 in the event of the bowl running over when 100 the water supply is shut off, there is preferably provided an enclosed member 50, having a restricted air opening 50' preferably in the bottom thereof, which communicates with the upper portion of the chamber 15 105 through the pipe 51. It will be seen that should the bowl overflow, the air admitted to the chamber 15 through the opening 50' will preclude the possibility of a vacuum being formed and the lifting up of the water 110 into the chamber. As an additional precaution against permitting the water from the bowl flowing back into the supply pipe, a check valve 52 may be mounted in the casing of the valve 45, this valve, as indicated 115 in Figure 3, permitting admission of water to casing 15 from pipe 20 but prevents it from flowing in the opposite direction.

By reason of the present construction, a very simple and efficient ventilating device 120 is provided for completely removing the noxious gases from the interior of the bowl. In addition to reducing to a minimum the waste of water, the device is so constructed as to be readily dismantled for the purpose 125 of inspection or renewal of any of the parts.

It will be understood that the form of the invention shown and described is merely illustrative, and in no sense restrictive, and that while the device is conventionally dis- 130

closed as applied to a water closet bowl, it may be used with urinals or like devices without departing from the spirit of the invention and the scope of the appended 5 claims.

We claim:

1. The combination with a water closet bowl and the waste pipe of the closet, of a 10 ventilating chamber communicating with the bowl, a seat for said bowl, means for creating suction through said chamber to withdraw foul air from the bowl comprising a perforated tube mounted within the 15 chamber, a supply pipe communicating with said tube, a valve for controlling the supply to said tube, means operatively connected to said seat and said valve for causing fluid to flow through said tube when the seat is lowered, and means communicating 20 with the atmosphere and connected to the ventilating chamber for preventing back suction of the liquid passing through the tube when the supply is shut off.

2. The combination with a water closet 25 bowl and the waste pipe of the closet, of a ventilating chamber communicating with the bowl, a seat for said bowl, means for creating suction through said chamber to withdraw foul air from the bowl comprising a perforated tube mounted within the 30 chamber, a supply pipe communicating with said tube, a valve for controlling the supply to said tube, means operatively connected to said seat and said valve for causing fluid to flow through said tube when the seat is lowered, and a member having a restricted 35 air opening in the bottom thereof communicating with said chamber to prevent back suction of the liquid when the supply is shut off.

3. The combination with a water closet 40 bowl and the waste pipe of the closet, of a ventilating chamber communicating with the bowl, means for creating suction through 45 said chamber to withdraw foul air from the bowl comprising a perforated tube mounted in said chamber and having inwardly projecting blades, a supply pipe communicating with said tube, a seat for said bowl, and 50 means operatively connected to said seat and pipe for causing fluid to flow through said tube when the seat is depressed.

4. The combination with a water closet 55 bowl, of a ventilating chamber communicat- 60 ing with the bowl and having a tapered flange on the inner wall thereof, a seat for said bowl, means for creating suction through said chamber to withdraw foul air from the bowl comprising a tube having a collar 65 adapted to engage said flange, said tube having openings therein above said collar and inwardly projecting blades below the collar, means connecting the upper end of the tube to the chamber, said means adapted to force the 70 collar into wedging engagement with

said flange when the parts are set up, a supply pipe communicating with said tube, and means for causing the fluid to flow through said tube when the seat is depressed.

5. The combination with a water closet 70 bowl, of a ventilating chamber communicat- 75 ing with the bowl, a seat for said bowl, means for creating suction through said chamber to draw the foul air from the bowl comprising a perforated tube mounted within the chamber, wedging means on said tube adapted to frictionally engage complementary means on the inner wall of the chamber for maintaining the former in position, and means operatively connected to 80 said pipe and seat for causing the fluid to flow through said tube when the seat is lowered.

6. The combination with a water closet 85 bowl, of a ventilating chamber communicat- 90 ing with the bowl, a seat for said bowl, means for creating suction through said chamber to draw the foul air from the bowl comprising a perforated tube mounted within the chamber, means within the tube for breaking up and aerating the liquid passing through the tube to facilitate commingling the liquid and foul air, wedging means on said tube adapted to frictionally engage complementary means on the inner wall of 95 the chamber for maintaining the former in position, and means operatively connected to said pipe and seat for causing the fluid to flow through said tube when the seat is lowered.

7. An attachment for bowls of the class 100 described comprising a chamber communicat- 105 ing with the bowl, a perforated tube extending within said chamber for drawing the foul air from the bowl, a supply pipe connected to said tube, a clamping nut connecting one end of the tube to said chamber, and wedging means on the interior of the chamber engaging complementary means in the tube for maintaining the opposite end of the tube in position, said means being controlled by the tightening up or loosening of the nut.

8. An attachment for bowls of the class 110 described comprising a chamber communicat- 115 ing with said bowl, said chamber having an annular flange on its inner wall provided with a tapered opening, a perforated tube extending within said chamber and having a tapered collar thereon for engagement with the flange on said chamber, and means connecting the upper end of the tube to the chamber, said means adapted to force the lower portion of the tube into wedging engagement with said chamber.

9. An attachment for bowls of the class 120 described comprising a chamber communicat- 125 ing with said bowl, said chamber having an annular flange on its inner wall provided with a tapered opening, a perforated tube extending within said chamber and having

a tapered collar thereon for engagement with the flange on said chamber, and means connecting the tube to the chamber, said means adapted to control the degree of engagement of the collar with the flange.

10. An attachment for bowls of the class described comprising a chamber communicating with said bowl, said chamber having an annular flange on its inner wall provided with a tapered opening, a perforated tube extending within said chamber and having a tapered collar thereon for engagement with the flange on said chamber, a nut for securing the upper end of the tube to said chamber, and means upon the tightening up

of said nut for forcing the collar into wedging engagement with said flange.

11. The combination with a water closet bowl and the waste pipe of the closet, of a ventilating chamber communicating at its upper end with the rim of the bowl and having an opening in the bottom communicating with the bowl below the water line thereof, and means for creating suction through the chamber to withdraw foul air from the bowl upon depression of the seat.

In testimony whereof we have hereunto set our hands.

EDWARD H. RAPER.
CHARLES E. RAPER.
